UNITED STATES PATENT OFFICE.

LUCIUS ANTON SMITH, OF BUFFALO, NEW YORK, ASSIGNOR OF ONE-HALF TO BEE BURN SMITH, OF BUFFALO, NEW YORK.

TRUSS PAD.

Application filed December 9, 1922. Serial No. 605,911.

To all whom it may concern:

Be it known that I, LUCIUS ANTON SMITH, a citizen of the United States, residing at Buffalo, in the county of Erie and State of New York, have invented new and useful Improvements in Truss Pads, of which the following is a specification.

The object of my said invention is the provision of a truss pad which because of its peculiar characteristics is materially advantageous over truss pads extant.

To the attainment of the foregoing, the invention consists in the improvement as hereinafter described and definitely claimed.

15 In the accompanying drawings, forming part of this specification:—

Figure 1 is a front elevation showing one of my novel pads as properly applied to a patient.

20 Figure 2 is a front elevation showing a portion of the human anatomy and also showing my novel pad as properly arranged for the amelioration of an oblique inguinal hernia.

25 Figure 3 is a section taken in the plane indicated by the line 3—3 of Figure 2.

Figure 4 is an elevation showing one edge of my novel truss pad—i. e., the edge that is designed to be arranged in parallelism with

30 the inguinal canal, and that is substantially straight in the direction of the length of the pad and also in the direction of the thickness of the pad, and is substantially perpendicular to the side of the pad remote

35 from the patient's body; said edge resting in use in a plane parallel to line 5—5 of Figure 2.

Figure 5 is a section taken in the plane indicated by the line 5—5 of Figure 2.

40 Figures 6 and 7 are views of the pad taken from different view points and illustrative of the portions of the pad that are opposed to the body of the patient; the pad in said views, however, being shown in substantially inverted positions.

Similar numerals of reference designate corresponding parts in all of the views of the drawings.

45 My novel truss pad is preferably, though not necessarily, a hard unyielding pad, and it is within the purview of my invention to form the pad of any material compatible with its purpose. In the embodiment illustrated the pad is provided with an outer and preferably flat side 1 for arrangement re-

mote from a patient's body, and in the said flat side 1 is a depression 2, preferably of circular configuration for the snug reception and connection of a plate 3 and a circular wire terminal 4, the plate 3 being connected with the pad through the medium of screws 5 and 6, and the wire terminal 4 being snugly confined in the depression 2 and interposed between the plate 3 and the bottom of the depression so as to be clamped and strongly held by the plate 3 and between the said plate and the pad. In this connection it will be noted that the snug arrangement of the wire terminal 4 which is of general circular form snugly against the side 70 wall of the depression 2 contributes materially to the strength of the connection between the pad and the wire 4^a comprised in the means for securing the pad on the body. It will also be noted that the pad is provided 75 in its side remote from the body of the patient with a groove 7 which extends from the depression 2 to the edge of the pad and is designed to seat the portion of the wire 4^a adjacent to the circular terminal 4 and by 80 so doing to contribute to the rigidity of the connection of the pad to the wire 4^a. This will be understood from Figures 1 and 2 of the drawings, and by particular reference to Figure 1 it will be understood that an 85 apertured tab 8 on straps 9 comprised in the securing means is adapted to be engaged with the screw 5 which is headed as illustrated.

The features described are material in 90 the respects indicated. I would have it understood, however, that the chief feature of my novel truss pad resides in the portion thereof that is opposed to the body of the patient. This portion comprises among 95 other features the edge of the pad best shown in Figure 4 and designated by 20. The said edge 20 is substantially perpendicular to the flat side 1 and is substantially straight in the direction of its length and also in the direction of the thickness of the pad, the latter characteristic being clearly illustrated in Figures 3 and 7 and the former characteristic being definitely illustrated in Figures 1, 2 and 6. The said portion of the pad that is opposed to the body of the patient also includes a longitudinal protuberance 21 that is in parallelism with and immediately adjacent to the said edge 20. As clearly brought out in Figures 3, 4, 5, 6, and 110

7 the said protuberance 21 is comparatively thick at the point 22, which point is located adjacent to the edge 20 and is also located materially nearer the upper end of the pad 5 when in use than the lower end thereof. From the said thick point 22 of the protuberance 21 the portion of the pad that is opposed to the body of the patient is merged into the concavity 23 at the side of the pad 10 opposed to the patient's abdomen and is also merged into the convexity 24 at the upper end of the edge 20, and the taper 25 that extends to the lower end of the pad adjacent to said edge 20.

15 In the application and use of the pad the substantially straight edge 20 thereof goes next to the thigh of the patient, and the concavity 23 goes next to the abdomen and hence makes for comfort and avoids pressure upon the bladder. In these connections it will be understood that the edge 20 substantially perpendicular to the flat side 1 and substantially straight in the direction of the length of the pad and also 20 in the direction of the thickness thereof enables the pad to bear against and close the inguinal canal of the patient throughout the length of the said canal, and hence less pressure of the pad will adequately hold 25 the rupture which will manifestly conduce to the comfort of the patient. The said edge 20 characterized as stated also renders it feasible for the fitting of the pad closer to the upper end of the inguinal canal than is 30 possible with pads extant. When the pad is arranged as stated relative to the inguinal canal, the protuberance 21-22 of the pad which is parallel and closely adjacent to the edge 20 affords the desired pressure against 35 and necessary to close the inguinal canal throughout the length thereof. From this it follows that closing of the inguinal canal is effected by the protuberance 21-22 of the pad and that the edge 20 of the pad renders 40 it feasible and easy to so position the pad as to enable the pad to serve the purpose stated in the most effective manner. This will be better understood when it is stated that the substantially straight edge 20 is 45 adapted to be positioned coincident with the inguinal furrow and off the inguinal ligament which enables the protuberance 21-22 to act most effectively against the part of the anatomy where the greatest pressure should 50 be applied, and this without interfering with movement of the thigh or being uncomfortable to the patient. It is well known to surgeons that the internal ring or upper end of the inguinal canal is the starting 55 point of oblique inguinal hernia; and in this connection it will be understood that the comparatively thick portion 22 of the protuberance 21 is adapted to penetrate further toward the interior of the patient's body 60 and in that way better act upon the inner wall of the inguinal canal at the upper end thereof. This great penetration of the comparatively thick portion 22 of the protuberance 21 is desirable in the treatment of bad cases, and greater or less penetration or 65 pressure of the said portion 22 is brought about by adjustment of the pad as occasion demands. As will be understood from Figure 3 the concavity 23 of the pad accommodates the pad to the abdomen of the patient 70 and practically does away with subjecting the patient to discomfort incident to the use of the pad. The said concavity also enables the protuberance 21-22 of the pad to better serve the purpose ascribed to the said protuberance while the edge 20 substantially straight in the two directions indicated and substantially perpendicular to the flat side 1, in addition to the purposes ascribed to the said edge 20 permits free movement of 75 the thigh of the patient without discomfort to the patient and without tendency to alter the position in which the pad is placed on the application thereof.

80 It is also to be understood that my novel pad is adapted to work satisfactorily for direct inguinal hernia and for femoral hernia as well as for oblique inguinal hernia which occurs most frequently; also, that between the protuberance 21 and the edge 20 the surface is essentially rounded.

85 However my novel pad is designed more especially for the amelioration of an oblique inguinal hernia, as hereinbefore indicated, the pad being positioned for such specific purpose as shown in Figure 2.

90 To effectively ameliorate such hernia by preventing the gut entering the inguinal canal through the internal ring, it is essential to close the internal ring of the inguinal canal by pressing the outer wall of said canal inwardly against the inner wall, the said ring being in the inner wall, and the closure of the ring being effected by the outer wall 95 acting under pressure against the inner wall, great inward pressure involving considerable penetration at a point coincident with the internal ring being necessary. It is also essential for practical results that the internal ring be closed and kept closed as 100 stated without subjecting the patient to great discomfort and pain. My novel pad is adapted to accomplish the purpose stated without the infliction of discomfort or pain on the patient largely because of the edge 20 essentially straight lengthwise and crosswise; and the protuberance portion 22, arranged relatively to the edge 20 and the remainder of the pad as defined. This will be 105 appreciated when it is stated that the edge 20 characterized as stated, stays off the inguinal ligament, and off and just above the pubic bone and because of the latter avoids pressure against the spermatic cord and binding of said cord against the pubic bone, 110

115

120

125

130

and this notwithstanding the necessary great penetration under considerable pressure of the protuberance portion 22 at precisely the proper point. In addition to the provision just stressed for averting the subjection of the patient to discomfort and pain while the protuberance portion 22 and protuberance 21 are functioning as described, the pad has the concavity 23 and the taper 25 which contribute to rendering the pad comfortable and painless.

I have entered into a detailed description of the construction and relative arrangement of the parts embraced in the present and preferred embodiment of my invention in order to impart a full, clear and exact understanding of the said embodiment. I do not desire, however, to be understood as confining myself to the specific construction and relative arrangement of parts inasmuch as in the future use of the invention various changes and modifications may be made such

as fall within the scope of my invention as defined in my appended claims.

Having described my invention, what I claim and desire to secure by Letters Patent, is:—

As a new article of manufacture, an inguinal hernia pad with an outer side and also with a portion for use in opposed relation to a patient's body, said portion characterized by an edge substantially constituting a plane straight in the directions of its length and width and lying substantially perpendicular to said outer side, and by a longitudinal protuberance immediately adjacent to said edge, comparatively thick at a point near the edge, and nearer the upper end of the pad than the lower end thereof; the remainder of said portion being generally tapered from said protuberance to the edge of the pad remote from said plane edge.

In testimony whereof I affix my signature.

LUCIUS ANTON SMITH.
